UNITED STATES PATENT OFFICE

BERT G. LARRABEE, OF HOUSTON, TEXAS

DESIGN FOR AN ASH TRAY

Application filed July 23, 1931. Serial No. 40,645. Term of patent 3½ years.

To all whom it may concern:

Be it known that I, BERT G. LARRABEE, a citizen of the United States, residing at Houston, in the county of Harris and State of Texas, have invented a new, original, and ornamental Design for an Ash Tray, reference being had to the accompanying drawing, forming a part hereof.

an ash tray, showing my new design; Figure II is a side elevation thereof; and Fig. 3 is a top plan view thereof.

I claim:

The ornamental design for an ash tray, as shown.

In testimony whereof, I hereunto affix my signature.

BERT G. LARRABEE
